UNITED STATES PATENT OFFICE.

THEODORE EVEN, OF CHICAGO, ILLINOIS, ASSIGNOR TO HAROLD
DYRENFORTH, OF SAME PLACE.

DESIGN FOR A BADGE.

SPECIFICATION forming part of Design No. 22,260, dated March 7, 1893.

Application filed October 28, 1892. Serial No. 450,284. Term of patent 14 years.

To all whom it may concern:

Be it known that I, THEODORE EVEN, a citizen of the United States, residing at Chicago, in the county of Cook and State of Illinois, 5 have invented and produced a new and original Design for a Badge, of which the following is a description, reference being had to the drawing, which illustrates the design.

The leading feature of the design consists 10 in the representation of the head of an elk, surmounted by a cross.

In the drawing A represents the head, and

B the cross, which latter is shown, in its proper position, as surmounting the head and extending between the antlers.

What I claim as new, and desire to secure by Letters Patent, is—

The design for a badge substantially as shown and described.

THEODORE EVEN.

In presence of—

DOUGLAS DYRENFORTH,
ALBERT FROMMANN.
